UNITED STATES PATENT OFFICE.

RUDOLPH FEDERROLL, OF NEW YORK, N. Y.

OIL-TANK.

SPECIFICATION forming part of Letters Patent No. 352,914, dated November 23, 1886.

Application filed September 23, 1886. Serial No. 214,334. (No model.)

To all whom it may concern:

Be it known that I, RUDOLPH FEDERROLL, a resident of New York city, in the county and State of New York, have invented an Improved Oil Tank and Pump, of which the following is a full, clear, and exact description, reference being made to the accompanying drawings, in which—

Figure 1 is a vertical central section of my improved oil-tank having a pump, the line x x , Fig. 2, showing the plane of section. Fig. 2 is a top view of said tank. Fig. 3 is a bottom view of the same. Fig. 4 is an enlarged vertical section showing the connection of the bottom of the tank with the side walls. Fig. 5 is an enlarged vertical section showing the means for securing the strainer. Fig. 6 is a detail section through the tube of the pump, showing how the parts of the same are united 20 to the carrying-frame.

This invention relates to certain improvements in the construction of metallic oil-tanks, being tanks intended to contain petroleum or the like, and a pump, with the aid of which a dealer can supply the consumer with limited quantities of the inflammable liquid.

The principal object of the invention is to render such a tank fire-proof, and also to make it compact for convenience in transportation.

The invention consists, first, in supplying such a tank with a reversible top, which, when in place for use, carries the diaphragm which separates the oil-containing chamber from the upper pump-chamber, and which has a movable lid for also closing the upper pump-chamber.

The invention also consists in a new means for securing the strainer to the diaphragm, and in a new construction of sectional pump-body 40 in combination with said diaphragm, all as hereinafter more fully described and claimed.

In the drawings, the letter A represents the vertical wall of my improved oil-tank. B is the bottom of the same, and C the top. The bottom B, which is made of sheet metal, has its edges turned down, as at a, (see Fig. 4,) so that said vertical portion a of the bottom shall come in contact with the inner side of the vertical wall A. A cast-metal trough-like plate, 50 D, receives this double lower portion of the tank in its cavity, as is also shown in Fig. 4,

and serves likewise to support with its inner wall, b, the outer part of the bottom proper, B.

Fig. 3 shows a bottom view of the trough D, representing it supplied with series of braces 55 d, giving it increased strength. Fig. 3 represents this bottom trough, D, as of circular form; but it may be of angular or oval form, if desired.

Into the upper part of the vertical body A 60 of the tank, which is supplied with a proper screw-thread, e, is screwed the top piece, C. This top piece consists of a threaded vertical wall, f, having outwardly-projecting lip g, and of the lower plate or diaphragm, h. The top 65 piece, C, is screwed into the body A until the lip g rests on the body of the tank. The diaphragm h constitutes a dividing-plate between the oil-chamber i, which is in the lower part of the tank, and the pump-chamber or working-chamber j, which is in the upper part. The top C also carries a rigid half-lid, l, and a movable half-lid, m. The movable half-lid can either be placed over the rigid half-lid, as is shown by full lines in Fig. 1, or it can be 75 turned, as shown by dotted lines m^x, so that the entire tank will be closed by the two lids l and m. To facilitate this turning I provide the movable half-lid m with a threaded portion, n, which matches the upper part of the 80 threaded portion f of the top C. In other words, a threaded ring, n, surrounds the upper part of the threaded ring f and carries the movable half-lid m, allowing the same to be turned either over the rigid half-lid l, as by 85 full lines in Fig. 1, or over the otherwise uncovered portion of the tank, as by dotted lines m^x in Fig. 1.

In transporting the tank I unfasten the top C and turn it upside down, so as to bring the 90 diaphragm h to the top of the tank and the lids l m into the body thereof. This is indicated by dotted lines in Fig. 1, and results in saving much room during transportation.

The diaphragm h is provided with a strainer, 95 o, which is fastened to said diaphragm by the means more clearly shown in Fig. 5—that is to say, the strainer proper is cup-shaped, the upright portion p of the cup being screw-threaded. This cup-shaped strainer is placed against the 100 under side of the diaphragm h, while from the top of said diaphragm a screw-ring, q, is in-

serted to engage with the threaded part *p*, thus holding the strainer in place; yet at any time, by simply unscrewing the ring *q*, the strainer can be detached and a large man-hole obtained, through which the interior of the tank can be inspected and repaired. The pump-body *E* is also made in sections, that are secured against the diaphragm *h*, as appears very clearly in Fig. 6 of the drawings—that is to say, the lower section, *r*, of the pump has a flange, *s*, which lies against the under side of the diaphragm *h*, while the upper portion, *t*, of the pump has a flange, *u*, that lies against the upper surface of the diaphragm *h*. A screw-ring, *v*, which projects from one of the pump-sections into the other, serves to unite them and to clamp the flanges *s* and *u* against the opposite sides of the diaphragm.

I claim—

- 1. The oil-tank *A*, combined with the reversible top *C*, substantially as and for the purpose specified.
- 2. The tank *A*, having threaded portion *e*, combined with the top *C*, having threaded por-

tion *f* and diaphragm *h*, substantially as and for the purpose specified.

3. The combination of the tank-body *A*, having threaded portion *e*, with the top *C*, having threaded portion *f* and rigid half-lid *l*, and with the threaded ring *n* and movable half-lid *m*, substantially as herein shown and described.

4. The combination of the diaphragm *h* with the cup shaped strainer *o*, having threaded upright portion *p*, and with the screw-ring *q*, substantially as and for the purpose herein shown and described.

5. The sectional pump *E*, consisting of the lower threaded portion, *r*, having flange *s*, upper portion, *t*, having flange *u*, and screw-ring *v*, in combination with the diaphragm *h*, against which the flanges *s* *u* are drawn when the sections are united by the screw-ring, substantially as herein shown and described.

RUDOLPH FEDERROLL.
